UNITED STATES PATENT OFFICE.

CLEMONS J. ZEBULON FANBERG, OF KERKHOVEN, MINNESOTA.

PLOW-TRIP.

1,331,424.

Specification of Letters Patent. Patented Feb. 17, 1920.

Application filed August 27, 1919. Serial No. 320,106.

To all whom it may concern:

Be it known that I, CLEMONS J. ZEBULON FANBERG, a citizen of the United States, residing at Kerkhoven, in the county of Swift 5 and State of Minnesota, have invented certain new and useful Improvements in Plow-Trips; and I do hereby declare the following to be a full, clear, and exact description of the invention, such as will enable others 10 skilled in the art to which it appertains to make and use the same.

My invention relates to improvements in plows, and has for its object to provide a pressure-released trip set to release a plow 15 when the pull thereon is increased above a predetermined amount due to striking a stone or other obstruction and thereby permit the plow to move out of working position and pass over the obstruction to avoid 20 breakage or other damage and, when out of working position, said plow may be automatically reset.

To the above end, the invention consists of the novel devices and combinations of devices hereinafter described and defined in 25 the claims.

In the accompanying drawings, which illustrate the invention, like characters indicate like parts throughout the several 30 views.

Referring to the drawings:—

Figure 1 is a fragmentary land side elevation of a plow having the invention incorporated therein, with some parts shown in 35 different positions by means of broken lines; and

Fig. 2 is a fragmentary plan view.

The numeral 3 indicates a plow rigidly secured to a relatively short primary beam 40 4 intermediately pivoted at 5 to the rear end of a secondary beam 6 which, as shown, comprises a pair of laterally spaced members between which the free end of the primary beam projects. An upwardly projecting 45 lock lever 7 extends between the members of the secondary beam 6 just forward of the primary beam 4 and is fulcrumed thereto at 8. Formed in the rear end of the lock lever 7, at its fulcrum 8, is a lock notch 9 having 50 on its upper side a tripping surface 10, and on its lower side a tripping surface 11. This lock notch 9 is adapted to receive the free end of the primary beam 4 to normally lock said primary beam to the secondary beam 6 against pivotal movement and thereby hold the plow in working position. 55

Located between the members of the secondary beam 6 is a rocker 12 mounted at its rear end on a transverse pivot pin 13 anchored in the members of said secondary beam. The rocker 12 is connected to the lock lever 7 by a pair of bars 14, one end of which is pivoted to the free or upper end of said rocker, and the other end of which is pivoted to the free or upper end of the lock lever 7. When the plow 3 is in working position, the lower edges of the bars 14 engage the pivot pin 13, for the rocker 12, as a stop and thereby limit the forward movement of the upper end of the lock lever 7. 70 In this position of the lock lever 7, the primary beam 4 engages the tripping surface 10 as a positive stop to hold the point of the plow 3 against upward movement in respect to the secondary beam 6. 75

The prongs of a U-shaped link 15 embrace the rocker 12 from the rear edge thereof and are pivotally connected thereto at 16. One end of a coiled spring 17 is attached to the transverse portion of the link 15, and the other end thereof is adjustably anchored by a turn buckle 18 to the secondary beam 6 just forward of the lock lever 7. It is important to note that the link 15, when the plow 3 is in working position, is below a dead center, 80 as shown by full lines in Fig. 1, so that the spring 17 yieldingly holds the lever 7 set. Obviously, by manipulating the turn buckle 18, the tension of the spring 17 may be varied at will. It will also be noted 90 that when the plow 3 is tripped out of working position, as shown by broken lines in Fig. 1, the pivotal connection 16 for the link 15 is on the other side of the dead center and thereby, through the spring 17, yieldingly holds the lock lever 7 in a released position. To permit this movement of the pivot 17 from one side of a dead center to the other, the link 15 is downwardly bent to afford clearance for the pivot pin 13. When 100 the lock lever 7 is in a released position, as shown by broken lines in Fig. 1, the bent intermediate portion of the link 15 engages the pivot pin 13 as a stop to limit the releasing movement of the lock lever 7. 105

In case the pull on the plow 3 is increased above the tension at which the spring 17 is set, due to the plow 3 striking a stone or other obstruction, said pull will cause the primary beam 4 to turn on its fulcrum 5 and 110 permit the point of the plow to move rearward and thereby pass over the obstruction,

This pivotal movement of the primary beam 4, acting on the tripping surface 11 with a cam action, will cause the lock lever 7 to move rearward, as indicated by broken lines 5 in Fig. 1. This rearward movement of the lock lever 7, acting through the bars 14, will lift the rocker 12 against the tension of the spring 17 and move the same rearward. During this movement of the rocker 12, the 10 pivotal connection 16 of the links 15 will move upward from one side to the other of a dead center, and, after passing above the dead center, the spring 17 will exert a pressure to move the rocker 12 rearward and 15 hence the lock lever will be moved therewith until stopped by the engagement of the link 15 with the pivot pin 13. The spring 17 will yieldingly hold the lock lever 7 in a released position until the plow is reset, as will now 20 be described.

To reset the plow, the rear end of the secondary beam 6 may be lifted by any suitable means, and the weight of the plow, when lifted from the ground, will cause the 25 plow to swing forward on its fulcrum 5 and thereby lift the free end of the primary beam 4 into engagement with the tripping surface 10 of the lock lever 7 with such force as to cause a forward movement of the lock 30 lever 7. The initial forward movement of the lock lever 7, acting through the bars 14, will swing the rocker 12 forwardly and downwardly and thereby carry the pivot 16 below the dead center, at which time the 35 spring 17 will exert sufficient force to cause the lock lever 7 to reengage the primary beam 4 and lock the same to the secondary beam against pivotal movement.

By reference to Fig. 1, it will be noted 40 that there is an extra hole in the rocker for the pivot which connects the bars 14 thereto into which said pivot may be adjusted to change the set position of the locker lever 7 and thereby lower the point of the plow in 45 respect to the secondary beam 6. It will also be noted that there is an extra hole into which the pivot 16 may be adjusted.

In place of lifting the rear end of the secondary beam 6 to reset the plow, said 50 secondary beam may be moved backward to cause the primary beam 4 to turn on its fulcrum 5 and thereby bring its free end into engagement with the tripping surface 10.

From the above description, it is evident 55 that a plow, once tripped out of working position, may be automatically reset without causing the operator to move from his position. While in the drawings only a single plow is shown, it is of course understood 60 that the invention is equally adapted for two-bottom plows.

What I claim is:—

1. The combination with a plow having primary and secondary beams, the former 65 of which is intermediately pivoted to the

latter, of a pressure-released lock lever fulcrumed on the secondary beam and provided with a lock notch having tripping surfaces on opposite sides thereof, said lock notch being arranged to receive the free end of the primary beam to hold the plow in working position, yielding means normally holding the lock lever in set and released positions, one of said tripping surfaces being arranged to be engaged by the primary beam when 70 the lock lever is released to reset said lock lever and thereby cause the same to automatically reengage and lock the free end of the primary beam when the plow is forced back to working position after being tripped out of the same. 80

2. The combination with a plow having primary and secondary beams, the former of which is intermediately pivoted to the latter, of a pressure-released lock lever fulcrumed on the secondary beam and provided with a lock notch having tripping surfaces on opposite sides thereof, said lock notch being arranged to receive the free end of the primary beam to hold the plow in 85 working position, yielding means normally holding the lock lever in set and released positions, one of said tripping surfaces being arranged to be engaged by the primary beam when the lock lever is released to reset said lock lever and thereby cause the same to automatically reengage and lock the free end of the primary beam when the plow is forced back to working position 90 after being tripped out of the same, and a 95 stop limiting the resetting movement of the lock lever.

3. The combination with a plow having primary and secondary beams, the former of which is intermediately pivoted to the latter, 100 of a lock lever fulcrumed on the secondary beam and provided with a lock notch having tripping surfaces on opposite sides thereof, said lock notch being adapted to receive the free end of the primary beam to hold the plow in working position, a rocker pivoted to the secondary beam, a bar pivotally connecting the lock lever to the rocker, and a spring operative on the rocker to 105 yieldingly hold the lock lever in set and released positions, one of said tripping surfaces being arranged to be engaged by the primary beam to reset the lock lever and thereby cause the same to automatically reengage and lock the free end of the primary beam when the plow is forced back to working position 110 after being tripped out of the same. 115

4. The combination with a plow having primary and secondary beams, the former 120 of which is intermediately pivoted to the latter, of a lock lever fulcrumed on the secondary beam and provided with a lock notch having tripping surfaces on opposite sides thereof, said lock notch being adapted 125

In testimony whereof I affix my signature
in presence of two witnesses.

CLEMONS J. ZEBULON FANBERG.
